(57) **CLAIM**

The ornamental design for a steering bezel, as shown and described.

DESCRIPTION

FIG. 1 is a side perspective view of a first embodiment of our design;

FIG. 2 is a side perspective view of the design of FIG. 1 shown from the opposite side;

FIG. 3 is a side elevational view;

FIG. 4 is a side elevational view from the side opposite to that of FIG. 3;

FIG. 5 is a front elevational view;

FIG. 6 is a side perspective view of a second embodiment of our design;

FIG. 7 is a side perspective view of the design of FIG. 6 shown from the opposite side;

FIG. 8 is a side elevational view;

FIG. 9 is a side elevational view from the side opposite to that of FIG. 8;

FIG. 10 is a front elevational view; and,

FIG. 11 is a rear elevational view common to all embodiments.

The dashed lines of the various figures are to illustrate environment and form no portion of the claimed design.
